UNITED STATES PATENT OFFICE.

JAMES SAMUELS, OF LYNN, MASSACHUSETTS, ASSIGNOR TO HIMSELF AND WILLIAM H. GALE, OF SAME PLACE.

IMPROVED MACHINE FOR SHAPING HEELS FOR BOOTS AND SHOES.

Specification forming part of Letters Patent No. 42,334, dated April 12, 1864.

To all whom it may concern:

Be it known that I, JAMES SAMUELS, a resident of Lynn, in the county of Essex and State of Massachusetts, have invented an Improved Machine for Shaping Heels for Boots or Shoes; and I do hereby declare the same to be fully described in the following specification, and represented in the accompanying drawings, of which—

Figure 1 is a top view, Fig. 2 a side elevation, and Fig. 3 a vertical and longitudinal section, of it.

In my said machine I make use of but one pattern for shaping a heel of any ordinary size, and employ with the said stationary or fixed pattern an adjustable cutter or knife, which is not only adjustable in directions toward and from the heel-clamp, but is provided with a means of lateral adjustment whereby the said cutter or knife may be still further adjusted with reference to the said heel-clamp or a piece of leather when fixed in the machine. Furthermore, I have a peculiar arrangement of a treadle and an auxiliary heel-cutter with reference to the table and stand for supporting the heel-clamp. I also have a peculiar arrangement of the spring which keeps the knife-carrier up to the pattern. The auxiliary knife-guide is also arranged so as to cause the said knife to make a slanting cut through the leather.

In the drawings, A denotes the table or stand of the machine, it being provided with an arm or standard, B, which is so applied to a post, C, as to be capable of sliding vertically thereon. Within the post C there is a spring, D, for forcing upward the standard B, which for being depressed is provided with a foot-treadle, E, the latter being connected with the standard by a connecting-rod, F, the whole being arranged as shown in the drawings.

For holding the treadle E down when depressed a stationary rack, G, extending from the table, is employed, the treadle being so applied to the table as to be capable of being engaged with the rack and disengaged therefrom as circumstances may require.

From a seat or projection, H, elevated on the table A, a cylindrical journal or post, I, projects upward and extends into and supports in position a pattern-cam, K, and a block, L, on which the leather or pieces of

leather to be shaped are to rest during the process of shaping or converting the same into a heel, the leather being held in place or stationary on the block L by means of a clamp, M, which extends downward from the movable standard B in manner as shown in Figs. 2 and 3.

Underneath the stationary pattern-cam K and embracing the post I, so as to be capable of revolving thereon, is a lever, N, in which there is a helical spring, O, which is provided with a head, x, that bears at one end against the post I, as shown in Fig. 3. This spring serves to draw the part a, by which the cutter-carrier b is supported, close up to the periphery of the pattern-cam, the head of the spring, while the lever is in the act of being revolved on the said post I, being caused to turn against the post and with the lever. The cutter-carrier b is dovetailed into the part a or into a dovetailed groove, c, which is arranged in such part a and transversely of the lever N, the groove admitting of the carrier being adjusted or moved laterally relatively to the lever. The cutter P, whose shank extends horizontally through the carrier b and is clamped therein by a screw, d, rests on the upper surface of the block or part a, in consequence of which the screw d can be used for two purposes—viz., that of fixing the cutter in its carrier and also that of clamping the latter to the block a. By revolving the lever N on the post I the cutter will be caused to traverse through the leather when clamped on the block L and the said cutter will be guided in the proper direction by means of the pattern-cam. Furthermore, there is applied to the standard B, and in advance of the clamp thereof, a chisel or auxiliary cutter, R, its shank being so applied to such standard as to be capable of moving up and down thereon. The cutter and its shank e are not arranged perpendicularly to the top surface of the block L, but are disposed at an inclination thereto so as to cause the cutter while being depressed to make a slanting cut through the leather. This cutter R is not only provided with an elevating-spring, S, arranged on one side of the standard B, but it has a means or mechanism for depression of such cutter, such being a lever, T, and a treadle, U, united by a connecting-rod, V, the whole being arranged as shown in the drawings, the lever T having its fulcrum

carried or supported by a projection, *f*, erected upon the standard *B*.

The part *a* hereinbefore mentioned has a journal, *g*, projecting vertically from it and into the lever *N*. This journal by revolving freely within the lever enables the part *a* to turn and adapt itself to the periphery of the pattern-cam, the form of the part *a* being as represented in top view in Fig. 4.

With my said machine I am enabled to effect the shaping of the front of the heel (by the auxiliary cutter or chisel) by means of a foot-treadle, instead of by a hand-lever, so applied to the standard *B* as to work transversely thereof and be operated by the hand of an attendant, thus operating more or less by the weight of the attendant's body rather than by the force of his arm alone, the treadle rendering it easier and less fatiguing for him to operate the machine in the matter of forcing the auxiliary cutter downward. By the peculiar means of adjustment of the main cutter it can be adjusted to better advantage as it may become worn or as circumstances may require than were it adjustable only in directions longitudinally of the lever by which it is operated.

I claim as my invention—

1. The improved machine as not only constructed with mechanism for supporting the leather and shaping it in the form necessary for a heel, but having a treadle, *U*, and an

auxiliary lever, *T*, arranged and combined together and with the table *A* and the movable standard *B*, substantially in manner and so as to operate as described.

2. The improved machine as not only constructed with mechanism for supporting the leather and shaping it in the form necessary for a heel, but as having its heel pattern cam stationary and its cutter *P* provided with adjusting devices, all substantially as described, whereby such cutter may be adjusted not only for heels of different sizes, but in other respects, as explained.

3. The arrangement of the cutter-carrier spring *O* within the lever *N*, and so as to bear by means of its head against and turn on the post *I*, substantially in manner and under circumstances as specified.

4. The improved machine as not only constructed with mechanism for supporting the leather and shaping it into the necessary form for a heel, but as having its auxiliary cutter or chisel *R* so arranged and applied to the standard *B* that while being depressed it will make a slanting cut through the leather or a cut inclined to the upper surface of the block for supporting the leather.

JAMES SAMUELS.
